UNITED STATES PATENT OFFICE.

LOUIE F. KOELLNER, OF ST. LOUIS, MISSOURI, ASSIGNOR TO HEINE BOILER COMPANY,
OF ST. LOUIS, MISSOURI, A CORPORATION OF MISSOURI.

INTERNAL MANDREL FOR HEADERS.

Application filed March 21, 1924. Serial No. 700,941.

To all whom it may concern:

Be it known that I, LOUIE F. KOELLNER, a citizen of the United States, residing at St. Louis, Missouri, have invented a certain new and useful Improvement in Internal Mandrels for Headers, of which the following is a full, clear, and exact description, such as will enable others skilled in the art to which it appertains to make and use the same.

This invention relates to sectional headers for boilers or similar structures of the general type disclosed in the pending applications for patent of Alfred Cotton Serial No. 596,432, filed October 23, 1922 and Serial No. 655,667, filed August 4, 1923.

The header described in the said Cotton applications is distinguished from the conventional serpentine boiler header principally by reason of the fact that it is constructed from a tube which is deformed by pressure applied externally to the tube in four different directions and in such a way as to press opposed portions of the tube inwardly and cause opposed portions of the tube to bulge outwardly, thereby producing a header whose lateral sides are made up of diametrically-opposed ridges and diametrically-opposed valleys arranged in alternate relation and whose front and rear sides are also made up of ridges and valleys arranged in alternate relation with each other and in staggered relation with the ridges and valleys on the lateral sides of the header. In manufacturing such a header the tube from which it is constructed can be deformed by a single operation or a continuous operation so as to produce a header having bulged portions of the kind mentioned and flat surfaces on its front and rear sides that constitute seats for the hand hole covers of the header and the boiler tubes which are connected to the header, or said tube can be deformed by one operation that produces the inwardly-pressed portions, the outwardly-bulged portions and partially formed seats, and thereafter subjected to a second operation wherein the seats are completed or finished in such a way that they will be of the required area.

My invention consists of a mandrel for internally supporting certain portions of a tube that is being deformed to produce

a header of the general design disclosed in the said Cotton applications, and adapted for use as a boiler header, a superheater header, or a header for connecting any kind of tubes.

One object of my invention is to provide a mandrel for the purpose described that is inexpensive to construct, of sufficiently rugged design to prevent it from being injured by rough handling, and of such construction that it can be removed easily from the header at the completion of the deforming or shaping operation.

Another object is to provide a mandrel for the purpose described which is of such a design that it can be modified easily to adapt it to the manufacture of headers of different lengths and headers having end portions of different shapes and dimensions.

To this end I have devised an internal mandrel that is composed of a number of pairs of members arranged end to end, lengthwise of the mandrel, and each member provided with a die element that is adapted to co-operate with an external die to form a flat surface on the inner side of the tube being deformed, said flat face being adapted to be used as a seat for a large tube or hand hole cover or for a plurality of small tubes or hand hole covers. When the mandrel is in use the various pairs of members that constitute the complete mandrel are held securely clamped together by pressure that is exerted on said pairs of members in a direction longitudinally of the header, and the two members that constitute each of said pairs are of such shape that one co-operates with the other to take up or resist the inward thrusts of the external dies, namely, the thrusts at right angles to the longitudinal axis of the mandrel. In order that the mandrel may be used successfully with a tube or header that is deformed or shaped while it is in a heated condition, I construct the mandrel in such a way that shrinkage of the tube or header, caused by the cooling of the metal of which it is constructed, will not result in the members constituting the mandrel being gripped by the tube or header in such a way as to interfere with the easy removal of said members. To this end I provide the two members of each of said pairs with op-

positively-inclined surfaces that bear against each other during the deforming operation, thus causing one member to support the other, and which are of such angularity 5 that if the endwise pressure on the pairs of members is relieved at the completion of the deforming operation, longitudinal or diametral shrinkage of the tube or header when it starts to cool will cause the two 10 members constituting each pair to move inwardly towards the longitudinal axis of the mandrel, thus partially collapsing the mandrel or reducing the transverse dimensions of same sufficiently to prevent the mandrel 15 from being gripped tightly by the tube or header when it contracts.

In the form of my invention herein illustrated the various pairs of members that make up the complete mandrel are held securely 20 clamped together by an element that extends longitudinally of the mandrel, and said pairs of members are provided with co-operating surfaces disposed at right angles to said longitudinally-disposed retaining element so as to cause each pair of members to bear evenly on the adjacent pair or on the two pairs of members between which it is arranged, when said retaining element is adjusted to clamp the pairs of 25 members together. It is preferable to construct said members in such a way that it is not necessary to thread the longitudinally-disposed retaining element through holes in said members of the same diameter as 30 the retaining element, as such a design enables the co-operating parts of the mandrel to be assembled and disassembled quickly and easily. With such a design, however, it is advisable to provide the two members 35 of each pair of members with co-operating means for maintaining said members in the same plane and also provide the various pairs of members with co-operating means 40 for preventing the adjacent pairs of members from moving out of alignment with each other. Due to the fact that the die elements on the mandrel and the external die that co-operate with said die elements 45 are of such shape that the pressure which the external dies exert on the mandrel during the deforming operation tends to force the members at one side of the center axis of the mandrel longitudinally in one direction and force the members at the other 50 side of the center axis of the mandrel longitudinally in the opposite direction, I arrange the members so that one member of each pair is disposed in diagonal relationship with a member of an adjacent pair 55 and with co-operating surfaces on said diagonally-disposed members bearing against each other in such a way that the endwise thrusts exerted by the external die on the members at the right hand side of the 60 longitudinal axis of the mandrel are bal-

anced by the endwise thrusts exerted by the opposed external die on the members at the left hand side of the longitudinal axis of the mandrel, thereby preventing the two members constituting each pair of members 70 from moving longitudinally of the mandrel in opposite directions.

Figure 1 of the drawings is a side elevational view of my improved mandrel, showing the pairs of members constituting the mandrel clamped together in operative position.

Figure 2 is a rear elevational view of said mandrel.

Figure 3 is a side elevational view of a 80 portion of the mandrel, showing it arranged inside of a tube that is to be pressed or deformed, so as to produce a sectional header of the kind disclosed in the said Cott- 85 ton applications.

Figure 4 is a view, illustrating the action of the front and rear dies on the tube inside of which the mandrel is arranged, the mandrel and external dies being shown in side elevation and the tube in longitudinal 90 section.

Figure 5 is a view, illustrating the operation of removing the mandrel members from the header at the completion of the deforming operation.

Figure 6 is a perspective view of one of the mandrel members.

Figure 7 is a perspective view, showing how the header looks at the completion of the deforming operation.

Figures 8 and 9 are a side elevational view and a rear elevational view of a mandrel of slightly different construction from the one shown in Figures 1 and 2.

Figure 10 is a perspective view of one 105 of the members of the mandrel shown in Figures 8 and 9.

Figure 11 is a top plan view of the apparatus that is used in the operation of assembling the members that constitute the 110 mandrel; and

Figure 12 is a side elevational view of said apparatus.

Referring to Figures 1 to 7 of the drawings which illustrate the preferred form of 115 my invention, A and A' designate a plurality of members that are combined in such a way as to form a mandrel which is adapted to be arranged inside of a tube x during the operation of deforming said tube so as to produce a sectional header of the kind shown in Figure 7 having lateral sides made up of diametrically-opposed ridges 1 and diametrically-opposed valleys 2 arranged in alternate relation, and front and rear sides made up of transverse ridges 1^a and valleys 2^a arranged in alternate relation with each other and in staggered relation with the ridges and valleys in the lateral sides of 125 the header. Said mandrel is provided with 130

die elements that co-operate with the external dies which act on the front and rear sides of the tube to form flat faces on the inner surfaces of the front and rear sides of the header that constitute seats for the hand hole cover gaskets and seats for the boiler tubes. When the mandrel is used in the manufacture of a sectional header designed for one and a half rows of staggered tubes and having tube seats and hand hole cover seats inclined slightly to the vertical, it is provided on its front and rear sides with groups of relatively wide die elements and groups of relatively narrow die elements arranged in alternate relation and equipped with inclined faces that co-operate with the external dies to form groups of wide and narrow flat surfaces y and z on the front and rear sides of the header, as shown in Figure 7, that are inclined slightly with relation to the longitudinal axis of the header, as shown more clearly in Figure 4. The wide and narrow flat surfaces y and z on the rear side of the header are adapted to have holes formed in same for receiving the tubes to which the header is to be connected, and the wide and narrow surfaces y and z on the front side of the header are adapted to have hand holes formed in same. Therefore, it is necessary that the wide and narrow portions y and z in the front and rear sides of the header have sharp angles and flat inner faces disposed at right angles to the longitudinal axis of the tubes so as to form seats for the tubes and seats for the gaskets that are used with the hand hole covers. Said mandrel is not restricted to use with any particular type or kind of external dies and the shape, form and arrangement of the die elements of the mandrel can be varied greatly without departing from the spirit of my invention. In manufacturing a sectional header of the kind disclosed in the said Cotton applications it is not necessary to internally support the portions of the tube on which the lateral side dies act, and therefore, I have only illustrated the front and rear external dies that co-operate with the mandrel to produce the flat hand hole cover seats and tube seats in the front and rear sides of the header. Moreover, while I have shown the front and rear external dies as consisting of two opposed, vertically-disposed dies that move horizontally towards and away from the longitudinal axis of the mandrel while the mandrel is stationarily supported, I do not wish it to be understood that the mandrel is limited to use with a deforming apparatus of this particular type or kind.

As previously stated, my improved mandrel is made up of a number of members A and A'. Said members are arranged in pairs with the pairs disposed in superimposed relation, as shown in Figures 1 and 2,

and means is provided for clamping said pairs of members together so as to produce a practically solid mandrel that can be arranged in an upright position in a vertical press equipped with opposed front and rear dies B and B'. Generally, the mandrel is arranged in an upright position in the press, a heated tube x is then slipped over the mandrel endwise, as shown in Figure 3, and thereafter, the external dies B and B' are moved inwardly towards the longitudinal axis of the mandrel so as to press the tube x into the shape shown in Figure 4. At the completion of the deforming operation the external dies are separated or moved outwardly and the endwise pressure on the mandrel members A and A' is relieved so as to permit the mandrel members to automatically move into such positions that they will not be gripped tightly by the header when it shrinks, due to the cooling of the metal of which it is constructed. Thereafter, the mandrel and the header inside of which it is arranged are removed as a single unit from the press.

Various means can be used for exerting endwise pressure on the mandrel members A and A', so as to clamp the pairs of members together, but I prefer to use a long rod or bolt C that extends longitudinally of the mandrel and which is provided at one end with a nut or equivalent element C' that is adapted to be turned in one direction to securely clamp the pairs of members A and A' together, and turned in the opposite direction so as to relieve the endwise pressure on said pairs of members. Preferably, the members A and A' are constructed in such a way that it is not necessary to thread the retaining element C through small holes in said members. In the form of my invention herein illustrated each of the members A and A' consists of a cast metal block provided with two side walls 3 and a connecting wall 4 disposed at substantially right angles to each other, as shown in Figure 6, thus forming a practically hollow member that is open at its inner side. The wall 4 is provided with an integral die element 5 that projects outwardly, and the side walls 3 are provided with inclined surfaces 6. As shown in Figure 1, the inclined surfaces 6 on the members A are disposed oppositely to the inclined surfaces 6 of the members A' so as to cause the two members constituting each of said pairs to back up each other to resist the inward thrusts of the external dies B and B'. In other words, when the members A and A' constituting the mandrel are assembled and clamped tightly together, the two members A and A' constituting each pair co-operate with each other to form a practically solid or rigid internal die that internally supports the opposed portions of the tube x that are

being pressed inwardly by the co-operating portions of the front and rear dies B and B'. At the completion of the deforming operation, after the adjustable device C' on the retaining element C has been backed off or loosened so as to relieve the endwise pressure on the pairs of members A and A', the inclined surface 6 of one member of each pair is free to slide over the inclined surface 6 of the member with which it co-operates when the header shrinks, due to the cooling of the metal of which it is constructed, thereby causing the mandrel to collapse sufficiently to prevent it from being gripped tightly by the header, but not sufficiently to completely disengage it from the header. The inclined portions 6 of the members A and A' are preferably machined surfaces, and while the angle of said surfaces can be varied greatly, I have found that if the angle of the surfaces 6, with respect to the face of the die element 5, is made approximately 20 degrees, that the co-operating members of the various pairs will mutually support each other during the deforming operation and will be capable of moving relatively to each other sufficiently, after the clamping device C' has been loosened, to eliminate the possibility of the mandrel being gripped tightly by the header when it shrinks. The various pairs of members A and A' that make up the complete mandrel are provided with co-operating surfaces disposed at substantially right angles to the retaining element C, that bear against each other when the nut C' on said retaining element is tightened. These surfaces may be comparatively small in area, because they do not sustain any of the compressive force utilized to deform the header, and in the form of my invention herein illustrated each of the mandrel members is provided at its upper and lower ends with two bearing surfaces, designated by the reference characters 7 and 7^a, formed preferably by the upper and lower ends of the connecting walls 4 of the mandrel member. As these surfaces 7 and 7^a are disposed at right angles to the retaining element C, the operation of tightening the adjustable device C' on the retaining element C causes all of the mandrel members at one side of the center axis of the mandrel to be clamped tightly together and causes all of the mandrel members at the other side of the center axis of the mandrel to be clamped tightly together.

Owing to the fact that the main function of the retaining element C and its co-operating adjustable device C' is to exert endwise pressure on the pairs of members A and A' so as to clamp them together, it is desirable to provide means for maintaining the pairs of members in longitudinal alignment with each other and to prevent the member A of each pair from moving transversely with

relation to its co-operating member A' in a direction to disengage the co-operating inclined surfaces 6 on said members or destroy the alignment of the die elements on said members with the external dies. Therefore, I prefer to provide the connecting wall 4 of each mandrel member with a recess 8 and a projection 9, located at opposite ends of said wall, as shown in Figure 6, so that when the various members A and A' are clamped together, as shown in Figure 1, the two members constituting each pair will be interlocked with an adjacent pair of members, or with the two pairs of members between which it is interposed. I also prefer to form the co-operating inclined surfaces 6 of each pair of members in such a way that they will interlock, which effect can be obtained by providing the inclined surface 6 of the member of one pair with a projection that fits in a depression or recess formed in the inclined surface of the co-operating member of the pair and designated by the reference character 10 in Figure 6. When the mandrel members are constructed in this way, the co-operating recess and projection on the inclined surfaces of the two members of each pair holds said members in alignment with each other and the co-operating recesses and projections 8 and 9 on the various pairs of members prevent said pairs from moving transversely out of longitudinal alignment with each other.

By referring to Figures 4 and 5 it will be noted that when the front and rear dies move inwardly to squeeze the tube against the mandrel and press it into the die elements 5 on the mandrel, there is a force tending to raise the mandrel members arranged at one side of the center axis of the mandrel and depress the mandrel members arranged at the opposite side of the center axis of the mandrel. This is partly due to the resistance of the metal of the tube to sharp bending and partly to the direct horizontal pressure of the dies tending to cause the members A and A' constituting each pair to slide along the inclined surfaces 6 on said members. In order to counteract this force I construct the mandrel members in such a way that one member of each pair co-operates with a diagonally-disposed member of an adjacent pair to counteract the endwise thrusts exerted on the mandrel members in directions tending to move the two members constituting a pair longitudinally in opposite directions. In other words, in my improved mandrel the members constituting the mandrel are of such construction and arrangement that the longitudinal thrust exerted on the members at one side of the center axis of the mandrel is balanced by the opposed longitudinal thrust exerted on the members at the other side of the center axis of the mandrel, thereby overcoming any

tendency of the two members constituting a pair of members to move longitudinally of the mandrel in opposite directions when the external dies move inwardly to deform the 5 tube inside of which the mandrel is arranged. In the form of my invention shown in Figures 1 to 6, inclusive, each of the members A is provided adjacent its upper end with surfaces 11, formed by inclined 10 portions at the upper end of the side walls 3 of said member, that bear against co-operating surfaces 12 on the lower end portion of the side walls of the diagonally-disposed member A' of the pair arranged immediately 15 above the same. Consequently, the upward thrust that is exerted on the members A of the mandrel by the front die B during the deforming operation is counteracted by the downward thrust that is exerted on the 20 members A' of the mandrel by the rear die B'. These co-operating surfaces 11 and 12 are preferably disposed at a considerable angle to the horizontal so as to permit of a relatively great longitudinal movement of 25 the members A with relation to the members A' after the endwise pressure on the various pairs of mandrel members has been relieved at the completion of the deforming operation. It is not absolutely essential that the 30 co-operating surfaces 11 and 12 of the mandrel members be inclined, for it is feasible to equip the members A and A' of the mandrel with horizontally-disposed co-operating surfaces 11^a and 12^a, as shown in Figures 8, 35 9 and 10, for counteracting the opposed longitudinal thrusts on the mandrel members during the deforming operation. However, when the mandrel members are provided with co-operating inclined surfaces 11 and 12, as in the form of my invention illustrated in Figures 1 to 6, inclusive, a slight slackening of the clamping device C' on the retaining element C at the completion of the 40 deforming operation permits the diagonally-opposed members of the mandrel to move a great distance relatively to each other, and thus eliminate the possibility of the mandrel members being gripped by axial or longitudinal shrinkage of the header. Another 45 advantage that results from providing the mandrel members with inclined co-operating surfaces 11 and 12 of the kind mentioned is that the members A' at the right hand side of the center axis of the mandrel are interlocked with the members A at the left hand side of the center axis of the mandrel in such a way that the members of the respective pairs are prevented from moving outwardly 50 away from each other. Consequently, the co-operating surfaces 11 and 12 on the mandrel members not only cause the diagonally-disposed members to co-operate with each other to balance the opposed endwise thrusts 55 exerted on the mandrel members by the pressing dies, but they also prevent the co- 60 operating members of the respective pairs from moving outwardly away from the center axis of the mandrel. The two pairs of members A and A' at the opposite ends of the mandrel are provided with die elements 5^a that co-operate with the external dies to 65 shape the end portions of the header, and the mandrel is provided at its lower end with a base piece 13 that is adapted to rest upon a bracket or other supporting structure 70 14 which sustains the mandrel. In the form of my invention herein illustrated the base piece 14 is provided with a groove 15 for receiving a bar or other similar device 16, 75 shown in Figure 4, that is used to center the mandrel. The base piece 14 is also provided with locating plates 17 on which the tube x is positioned preparatory to the deforming operation. To facilitate accurately centering the tube relatively to the mandrel the 80 locating plates 17 are provided with sloping surfaces that cause the tube to be automatically centered with relation to the longitudinal axis of the mandrel when the tube is slipped down over the mandrel during the 85 operation of arranging the tube in the press. 90

In using my improved mandrel to produce a header of the kind shown in Figure 7, the mandrel is first arranged in an upright position in the press between the front and rear dies B and B' and a heated tube x is then lowered into position surrounding the mandrel and resting centrally upon the locating plates 17. The press is then set in operation 95 so as to cause the external dies to move inwardly into engagement with the tube, thus causing the front and rear dies to co-operate with the die elements 5 on the mandrel members A and A' to produce flat, 100 sharp-angled, inclined surfaces 1^a and 2^a in the front and rear sides of the header. The squeezing of the tube on the mandrel tends to cause the mandrel members A and A' to slide on the co-operating inclined surfaces 110 6 on the said members, and thus elongate the mandrel as a whole, but this tendency of the mandrel members to slide is prevented by the retaining element C which exerts endwise pressure on the pairs of mandrel members to hold the co-operating surfaces 7 and 7^a of said members pressed tightly together. After the tube has been deformed by the 115 inward movement of the external dies the nut C' at the upper end of the retaining element C is loosened or backed off slightly so as to relieve the endwise pressure on the pairs of members A and A' that make up the mandrel, and thus permit the two opposed members of each pair to move inwardly and also longitudinally sufficiently 120 to prevent said members from being gripped tightly by the header when it shrinks, due to the cooling of the metal of which it is constructed. The mandrel and the header 125 130

are then lifted as a single unit out of the press and laid on a table or other supporting structure while the retaining element C and mandrel members A and A' are withdrawn 5 from the header, as shown in Figure 5.

In assembling the parts of the mandrel it is preferable to use an assembling apparatus of the kind shown in Figures 11 and 12, which is composed of a hinged or pivotally-mounted table 18 that is adapted to be arranged in a horizontal position, as shown in Figure 12, during the assembling operation, and which is provided on its top side with a plurality of locating brackets 19. The 10 mandrel members A and A' are arranged flatwise on the table 18 with the flat face of the die elements 5 on said members bearing against the locating brackets on the table, as shown in broken lines in Figure 11, 15 and after the mandrel members have been assembled the retaining element C is moved longitudinally through the same and the nut C' is screwed onto the end of the element C so as to clamp the members together. 20 The table 18 is then swung into and upright position, as shown in broken lines in Figure 12, and a crane hook is then inserted in the ring 20 on the nut C' of the retaining element and the mandrel thereafter removed 25 to the press where it is to be used or to the point where it is to be stored.

A mandrel of the construction above described can be assembled and disassembled quickly and easily, as it is composed of a 30 plurality of pairs of members that are combined in such a way that they readily fall apart as soon as the nut C' of the retaining element C is removed. Such a mandrel can be modified easily to adapt it to the manufacture of headers of various lengths and 35 headers having end portions of different shapes and dimensions, and as it is composed principally of cast metal members, it is strong and rugged enough to successfully 40 withstand rough handling. In addition to the desirable features above pointed out, my improved mandrel is of such design that there is no liability of its being gripped tightly by the header when it shrinks or 45 contracts, because the members constituting the mandrel are so constructed and combined that a slight slackening or backing off the nut C' of the retaining element permits the 50 mandrel members to move inwardly, thus 55 allowing for diametral shrinkage and also move lengthwise of the mandrel, thus allowing for longitudinal shrinkage of the header.

Having thus described my invention, 60 what I claim as new and desire to secure by Letters Patent is:

1. An internal mandrel that is adapted to be arranged inside of a tube that is being deformed to produce a header, said mandrel 65 being composed of a plurality of pairs of

separable members arranged end to end and provided with die elements that are adapted to co-operate with external dies to form flat seat faces on the front and rear sides of the header, and means for holding said members 70 immovable or in rigid relation with each other during the deforming operation.

2. An internal mandrel for the purpose described, composed of a plurality of pairs of separable members arranged end to end 75 and each provided with a die element that is adapted to co-operate with an external die to form a flat seat face on a tube inside of which the mandrel is arranged, and means for exerting endwise pressure on said members and maintaining them in rigid relationship with each other during the operation 80 of deforming the tube.

3. An internal mandrel for the purpose described, composed of a plurality of pairs 85 of separable members arranged end to end and each provided with a die element that is adapted to co-operate with an external die to form a flat seat face on a tube inside 90 of which the mandrel is arranged, means for exerting endwise pressure on said members to maintain said pairs in operative relationship with each other, and co-operating inclined surfaces on the members of each 95 pair disposed so that said members are capable of moving slightly relatively to each other after the endwise pressure on said members has been relieved.

4. An internal mandrel for the purpose 100 described, composed of a plurality of members arranged end to end and provided with die elements that are adapted to co-operate with external dies which act on the tube inside of which the mandrel is arranged, means for exerting pressure on said members longitudinally of the mandrel, co-operating surfaces on said members disposed so as to cause said pairs of members to be clamped together by said pressure, and co-operating inclined surfaces on the two members constituting each pair disposed so 105 that one member backs up the other to resist the inward force of the external dies during the deforming operation but the co-operating members of the respective pairs are capable of moving inwardly towards the longitudinal axis of the mandrel after the longitudinal pressure on the pairs of members has been relieved.

5. An internal mandrel for the purpose 110 described, composed of a plurality of pairs of members arranged end to end and provided with die elements that are adapted to co-operate with external dies which act on the tube inside of which the mandrel is arranged, means for exerting sufficient endwise pressure on said pairs of members to hold them immovable or in rigid relationship with each other during the deforming 115 operation, and means for holding the two 120 members immovable or in rigid relation with each other during the deforming operation.

members constituting each of said pairs in alignment with each other.

6. An internal mandrel for the purpose described, composed of a plurality of pairs of members arranged end to end and provided with die elements that are adapted to co-operate with external dies which act on the tube inside of which the mandrel is arranged, means for holding said members in rigid relation with each other during the deforming operation, and an independent means for maintaining the respective pairs of members in longitudinal alignment with each other.
- 15 7. An internal mandrel for the purpose described, composed of a plurality of pairs of members arranged end to end and provided with die elements that are adapted to co-operate with external dies which act on the tube inside of which the mandrel is arranged, means for exerting endwise pressure on said pairs of members in such a way as to hold them immovable or in rigid relation with each other during the deforming operation, means for maintaining the members of each pair in alignment with each other, and an independent means for maintaining the respective pairs of members in longitudinal alignment.
- 20 8. An internal mandrel for the purpose described, composed of a plurality of pairs of members arranged end to end and each provided with a die element that is adapted to co-operate with an external die that acts on the tube inside of which the mandrel is arranged, means for holding said members in rigid relationship with each other during the deforming operation, and co-operating surfaces on said mandrel members disposed so that longitudinal thrusts exerted on the members at one side of the center axis of the mandrel tending to move said members in one direction counteracts thrusts exerted on the members at the other side of the center axis of the mandrel tending to move said members longitudinally in the opposite direction.
- 25 9. A mandrel for the purpose described, composed of pairs of members arranged end to end, means for exerting endwise pressure on said members to hold them immovable during the deforming operation and co-operating surfaces on said mandrel members for counteracting thrusts exerted on said members by the external dies in directions tending to force the members of each pair longitudinally in opposite directions.
- 30 10. An internal mandrel composed of a plurality of pairs of members arranged end to end and each provided with a die element that is adapted to co-operate with an external die which acts on the tube inside of which the mandrel is arranged, means for preventing said members from moving relatively to each other during the de-

ing operation, and co-operating interlocking portions on the two members of each of said pairs.

11. An internal mandrel composed of a plurality of pairs of members arranged end to end and provided with die elements that are adapted to co-operate with an external die which acts on the tube inside of which the mandrel is arranged, means for holding said members immovable or in rigid relation with each other during the deforming operation, and co-operating interlocking portions on the respective pairs of members.

12. An internal mandrel composed of a plurality of pairs of members arranged end to end and provided with die elements that are adapted to co-operate with an external die which acts on the tube inside of which the mandrel is arranged, means for holding said members in rigid relationship with each other during the deforming operation, interlocking portions on the two members constituting each of said pairs, and interlocking portions on the respective pairs of members.

13. An internal mandrel for the purpose described, composed of a plurality of pairs of members arranged end to end and provided with die elements that are adapted to co-operate with the external dies that act on the tube inside of which the mandrel is arranged, the two members constituting each of said pairs being provided with oppositely-inclined surfaces that bear against each other during the deforming operation, means for exerting endwise pressure on the pairs of members to clamp them together, and means for maintaining the two members constituting each of said pairs in alignment with each other and for maintaining the respective pairs of members in longitudinal alignment when the endwise pressure on said pairs of members is relieved at the completion of the deforming operation.

14. An internal mandrel for the purpose described, composed of a plurality of pairs of members arranged end to end and each provided with a die element that is adapted to co-operate with an external die that acts on the tube inside of which the mandrel is arranged, said pairs of members being so constructed and combined that one member of each pair is disposed in diagonal relationship with the opposite member of an adjacent pair and with co-operating surfaces on said diagonally-disposed members bearing against each other, and means for holding said members immovable or in rigid relation with each other during the deforming operation.

15. An internal mandrel for the purpose described, composed of a plurality of pairs of members arranged end to end, co-operat-

- ing inclined surfaces on the two members of each pair, means for exerting endwise pressure on said pairs of members to hold them in rigid relation with each other during the deforming operation, said means being adapted to be manipulated at the completion of the deforming operation so as to relieve the end pressure on said pairs of members and permit the mandrel to collapse sufficiently to provide for the shrinkage of the header inside of which it is arranged, and co-operating interlocking portions on said pairs of members that prevent said members from moving outwardly away from the center axis of the mandrel.
16. An internal mandrel for the purpose described, composed of a plurality of pairs of members arranged end to end and each provided with a die element that is adapted to co-operate with an external die which acts on the tube inside of which the mandrel is arranged, means that is adapted to be manipulated to clamp said pairs of members together during the deforming operation and to thereafter relieve the endwise pressure on said members, and co-operating surfaces on the pairs of members disposed so as to permit of a relatively great diagonal movement of said members without collapsing the mandrel to such an extent as to disengage it from the header.
17. An internal mandrel for the purpose described, composed of a plurality of members arranged end to end and each provided with a die element that is adapted to co-operate with an external die that acts on the tube inside of which the mandrel is arranged, a retaining element arranged longitudinally of said members for exerting endwise pressure on same to clamp them together, co-operating inclined surfaces on the two members of each of said pairs, and independent co-operating surfaces on the members of the respective pairs disposed at substantially right angles to said retaining element.
18. An internal mandrel for the purpose described, composed of a plurality of members arranged end to end and each provided with a die element that is adapted to co-operate with an external die that acts on the tube inside of which the mandrel is arranged, a retaining element arranged longitudinally of said members for exerting endwise pressure on same to clamp them together, co-operating inclined surfaces on the two members of each of said pairs, independent co-operating surfaces on the members of the respective pairs disposed at substantially right angles to said retaining element, co-operating inclined surfaces on the two members of each of said pairs, independent co-operating surfaces on the members of the respective pairs disposed at substantially right angles to said retaining element, co-operating interlocking portions on the inclined surfaces of said members, and co-operating interlocking portions on the respective pairs of members.
19. An internal mandrel for the purpose described, composed of a plurality of pairs of members arranged end to end, means for holding said members in rigid relationship with each other during the deforming operation and means at one end of the mandrel for centering a tube that is slipped over the mandrel.
20. An internal mandrel for the purpose described, composed of a plurality of pairs of members arranged end to end with the two members of each pair disposed oppositely to each other and the opposite members of adjacent pairs in diagonal relationship, a die element on each of said members, a retaining element arranged longitudinally of the mandrel for exerting endwise pressure on the pairs of members during the deforming operation and provided with an adjustable element that is adapted to be manipulated to relieve said endwise pressure at the completion of the deforming operation, co-operating inclined surfaces on the two members of each pair disposed so as to permit said members to move inwardly towards the longitudinal axis of the mandrel and thus allow unrestricted shrinkage of the header inside of which the mandrel is arranged, co-operating surfaces on the respective pairs of members disposed at substantially right angles to said retaining element, and co-operating surfaces on the diagonally-disposed members that prevent movement of said members away from the longitudinal axis of the header, prevent the two members of each pair from moving longitudinally in opposite directions and which allow considerable diagonal movement of the various members constituting the mandrel when the endwise pressure on said members is relieved.

LOUIE F. KOELLNER.
